Matthew B. Blish, Oak Park, Ill.

Application December 4, 1953, Serial No. 27,916

Term of patent 14 years

(Cl. D74—21)

To all whom it may concern:

Be it known that I, Matthew B. Blish, a citizen of the United States, residing at Oak Park, in the county of Cook and State of Illinois, have invented a new, original, and ornamental Design for a magnetic Pencil Holder or Similar Article, of which the following is a specification, reference being had to the accompanying drawing, forming a part thereof.

Fig. 1 is a front elevational view of a magnetic pencil holder showing my new design;

Fig. 2 is a side elevational view thereof partly in section;

Fig. 3 is a rear elevational view;

Fig. 4 is a sectional view taken along the line 4—4 of Fig. 1; and

Fig. 5 is a sectional view taken along the line 5—5 of Fig. 3.

I claim:

The ornamental design for a magnetic pencil holder or similar article, substantially as shown.

MATTHEW B. BLISH.
